UNITED STATES PATENT OFFICE

1,996,890

MANUFACTURE OF SHOES

Chester D. Turner, Manchester, N. H., assignor
to United Shoe Machinery Corporation, Paterson, N. J., a corporation of New Jersey

Application May 9, 1934, Serial No. 724,654

6 Claims. (Cl. 12—145)

This invention relates to the manufacture of shoes, and more particularly to the fastening of shoe uppers adhesively in lasted relation to insoles or other shoe bottom parts (hereinafter frequently referred to generically as soles). The invention is herein illustrated by reference to the lasting of the toe ends of shoes of a type in which the margin of the upper in lasted position lies in generally parallel relation to the bottom of the last; but it is to be understood that it is not limited to the manufacture of shoes of that type nor limited to the lasting of the toe ends of shoes.

An object of the invention is to provide a method whereby adhesive may be utilized to fasten uppers in lasted position with a saving of time in the lasting operation as compared with methods heretofore commonly in use, and without such inconveniences as may be involved in the use of liquid adhesive, including the necessity for care to insure that the adhesive shall be applied uniformly and in proper quantity and that none of it shall contact with a part of the shoe where its presence would be objectionable. To this and other ends, there is herein disclosed a novel method whereby a piece of adhesive sheet material, including a normally tacky or non-drying adhesive such as to require no treatment to put it in condition to adhere to a part pressed against it, is utilized for fastening uppers in the lasting operation. While the method may be practiced by the use of adhesive sheet material of various kinds or compositions, I have obtained successful results with what is known commercially as Scotch tape, which has been extensively used heretofore in shoe manufacture for reinforcing parts of uppers and for other purposes. Such tape, as used in shoe manufacture, commonly comprises a sheet or strip of tough paper provided with a normally tacky adhesive on both sides thereof, but having a protective cover of paper over the adhesive on one side. The adhesive may be, for example, of the character disclosed in Letters Patent No. 1,814,132, granted on July 14, 1931 upon an application of Richard G. Drew. It is contemplated that in the practice of the method of this invention a piece or strip of such tape of suitable size and shape will be applied to a sole or to an upper, preferably before the upper and the sole are assembled on a last, with that side of the piece on which the protective cover is located outermost. It will be understood that the piece thus applied will adhere firmly to the sole or the upper when pressed against it. The protective cover will thereafter be left on the piece until that stage in the manufacture of the shoe when the margin of

the upper is to be fastened in lasted relation to the sole, whereupon it will be removed to expose the adhesive. This may be done by simply pulling the cover off the adhesive. In the lasting of the toe of a shoe, for example, in this manner the protective cover will prevent the upper materials from adhering to the sole during the earlier stages of the lasting operation, including the wiping of the margin of the materials one or more times inwardly over the sole before trimming away the margin of one or more of the layers of the materials as is customary in lasting toes with adhesive. It is contemplated that it will be preferable under most conditions to apply the adhesive piece to the sole, although it may be applied to the upper instead, if desired.

The novel method will now be more particularly described by reference to the accompanying drawing and thereafter pointed out in the claims.

In the drawing,

Fig. 1 is a perspective view of the forepart of an insole showing an adhesive piece or strip applied to the toe end thereof for purposes of this invention;

Fig. 2 is a section on the line II—II of Fig. 1 on an enlarged scale;

Fig. 3 is a perspective view illustrating how the margin of the toe end portion of the upper materials may be wiped inwardly over the insole in a bed-lasting machine while the protective cover is on the adhesive strip;

Fig. 4 is a sectional view of the toe end of the last and the shoe materials at that stage in the lasting operation represented by Fig. 3;

Fig. 5 is a perspective view illustrating the removal of the protective cover from the adhesive strip after the margin of the lining and toe box have been trimmed away around the toe;

Fig. 6 is a view similar to Fig. 4, illustrating the wiping of the margin of the upper into final lasted position over the adhesive strip after the cover has been removed from the strip;

Fig. 7 is a perspective view of the forepart of an insole having on the toe end thereof an adhesive piece of different shape from that shown in Fig. 1; and

Fig. 8 illustrates how an adhesive strip may be applied to the outer layer of the toe end of the upper materials instead of to the insole.

In accordance with one mode of procedure in practicing the method of this invention, there will be cut from Scotch tape, for example, a substantially U-shaped adhesive strip 10 to overlie the margin of the toe end of an insole over which the margin of the upper is to be lasted, and the

strip will be applied to the toe end of the insole 12 as illustrated in Fig. 1. As previously explained, such tape has a protective cover 14 over the adhesive on one side thereof, and when the strip prepared as described is applied to the insole, this cover will lie at the outer side of the strip. It will be understood that the normally tacky adhesive on the other side of the strip will fasten the strip firmly to the insole when it is pressed against the insole without the necessity for any preliminary treatment of the adhesive. After insoles have been prepared in this manner they may be stacked or handled freely without any danger of adhering to one another, by reason of the presence of the protective cover on each adhesive strip. Such an insole will be mounted on a last and the upper will be assembled on the last in the usual manner, after which the customary pulling-over operation may be performed. Thereafter the shoe may be lasted along the sides in any suitable well-known manner, the drawing showing a shoe in which the upper is fastened in lasted position along the sides by staples 16 (Figs. 3 and 5) driven as disclosed in Letters Patent No. 1,815,296, granted on July 21, 1931 upon an application of George Goddu. After the side-lasting operation the shoe is placed in a bed-lasting machine and in the use of this machine the margin of the upper materials around the toe is wiped inwardly over the insole by the toe wipers 18 with which such machines are provided, as illustrated in Figs. 3 and 4. As shown in the drawing, the upper materials comprise an outer layer 20 which may be of leather, a middle layer 22 consisting of a toe box, and an inner layer 24 consisting of a lining. It will be understood that the number of such layers may vary in shoes of different kinds or styles. The margins of all the layers of the upper materials are wiped inwardly over the insole at that stage in the lasting operation represented by Figs. 3 and 4, and after one or more such overwiping operations the wipers are retracted from over the shoe bottom. It will be understood that the protective cover 14 on the adhesive strip prevents the fastening of the inner layer, i. e., the lining, to the insole in this overwiping operation. After the wipers have been retracted the operator, in accordance with the usual practice, trims away the margin of each layer of the upper materials around the toe except the outer layer 20 so that the layers thus trimmed will overlap the bottom face of the insole only to a very small extent. The shoe being now ready for the margin of the outer layer to be wiped inwardly over the insole into finally lasted position, the operator removes the protective cover 14 from the adhesive strip by pulling it off the adhesive 26 on the strip, as illustrated in Fig. 5, thus exposing the adhesive. The wipers 18 are then again advanced and closed to wipe the margin of the upper over the insole and are operated in the usual manner to press the margin down upon the insole, in which operation the adhesive strip is immediately effective to fasten the upper firmly to the insole (Fig. 6). The wipers may then be at once withdrawn from over the shoe bottom, since continued pressure on the margin of the upper is unnecessary.

Instead of using an adhesive piece or strip 10 of the form illustrated in Fig. 1, a piece 28 of the form shown in Fig. 7 may be utilized, this piece having, like the strip 10, an edge contour corresponding to that of the edge of the toe end of the insole, but extending entirely across the insole from side to side. If desired, moreover, in-

stead of applying an adhesive piece to the insole, such a piece may be applied to the upper, for example to the outer layer 20 of the upper materials. In this case there may be utilized a strip 30 (Fig. 8) curved to lie along the margin of the inner face of the outer layer of the upper materials around the toe, the protective cover 14 of the strip lying at that side of the strip which is next to the toe box 22. Such a strip will preferably be applied at a time before the upper is assembled on the last. With the strip thus applied to the upper, the margins of the several layers of the upper materials will be wiped inwardly over the insole in the same manner as hereinbefore described, the cover on the adhesive strip at this time preventing the margins of the two outer layers of the materials from being fastened together by the adhesive. The protective cover will thereafter be removed from the strip at the same stage in the lasting operation as illustrated by Fig. 5, and when the margin of the upper is thereafter wiped into finally lasted position the adhesive strip thereon will fasten it to the insole, the margins of the two inner layers of the upper materials having been trimmed away as described.

From the foregoing description it will be evident that the invention provides a method whereby uppers may be conveniently secured in lasted position by the use of adhesive with a substantial saving of time on the part of the lasting machine operator as compared with methods heretofore in use, since all that the operator has to do to render the adhesive effective is to remove the protective cover 14 from the adhesive piece or strip and since there is no need to maintain pressure on the margin of the upper for any substantial length of time after wiping it into final lasted position. By this method, moreover, the care required in applying liquid adhesive is eliminated, and also the danger of applying an excess of adhesive or of applying it on parts of the shoe where its presence would be objectionable.

While the invention is herein illustrated by reference to the use of an adhesive piece or strip having adhesive on both sides thereof and a protective cover on one side, it is to be understood that it is not limited to the use of a strip having adhesive on the side thereof next to the part to which the strip is first applied, since the strip may be secured to that part otherwise than by means of adhesive on the strip.

Having described the invention, what I claim as new and desire to secure by Letters Patent of the United States is:

1. That improvement in methods of making shoes which consists in applying to one of the parts of a shoe, for fastening the shoe upper adhesively in lasted relation to a sole, a piece of adhesive sheet material having on the opposite side thereof from the part to which the piece is thus applied a normally tacky adhesive protected by a cover, and before laying the marginal portion of the upper in finally lasted relation to the sole removing said protective cover to expose the adhesive.

2. That improvement in methods of making shoes which consists in applying in adhering relation to one of the parts of a shoe, for fastening the shoe upper adhesively in lasted relation to a sole, a piece of adhesive sheet material having a normally tacky adhesive on both its sides and a protective cover over the adhesive on the opposite side thereof from the part to which the

piece is thus applied, and before laying the marginal portion of the upper in finally lasted relation to the sole removing said protective cover to expose the adhesive.

- 5 3. That improvement in methods of making shoes which consists in applying to an end of a sole a piece of adhesive sheet material having on the opposite side thereof from the sole a normally tacky adhesive and a protective cover over the adhesive, laying the margin of an end of an upper preliminarily inward over that portion of the sole where said piece is located while said cover is in place, thereafter releasing the margin of the upper and removing the cover from the piece of adhesive material, and after the removal of the cover laying the margin of the upper again inward over the sole and pressing it against the adhesive.
- 10 4. That improvement in methods of making shoes which consists in applying in adhering relation to the toe end of a sole an adhesive strip having a normally tacky adhesive on both its sides and a protective cover over the adhesive on the opposite side thereof from the sole, wiping the margin of the toe-end portion of upper materials inwardly over the strip on the sole while said cover is in place, thereafter releasing the margin of the upper materials and trimming the margin of one or more of the layers of the materials around the toe, removing the cover from the adhesive strip, and after the removal of the cover wiping the margin of the upper which remains after the trimming again inward over the sole and pressing it against the adhesive strip.

5 5. That improvement in methods of making shoes which consists in applying to the margin of an upper an adhesive strip having on the opposite side thereof from the upper a normally tacky adhesive and a protective cover over the adhesive, laying the margin of the upper preliminarily inward over a sole while said cover is in place, thereafter releasing the margin of the upper and removing the cover from the adhesive strip, and after the removal of the cover laying the margin 10 of the upper again inward over the sole and pressing it into position for the adhesive strip to fasten it to the sole.

6. That improvement in methods of making shoes which consists in applying in adhering relation to the margin of the outer layer of the toe-end portion of upper materials an adhesive strip having a normally tacky adhesive on both its sides and a protective cover over the adhesive on the opposite side thereof from said layer, wiping 15 the margin of the toe-end portion of the upper materials inwardly over a sole while said cover is in place, thereafter releasing the margin of the upper materials and trimming the margin of all but the outer layer around the toe, removing the 20 cover from the adhesive strip, and after the removal of the cover wiping the margin of the outer layer to which said strip is applied again inwardly over the sole and pressing it into position to be 25 fastened to the sole by said strip. 30
